TREATING LIQUID PARTIAL OXIDATION PRODUCTS

Joseph Hidy James, Pittsburgh, Pa., assignor to
Clarence P. Byrnes, trustee, Sewickley, Pa.No Drawing. Application May 31, 1921,
Serial No. 473,798

18 Claims. (CL 196—142)

In several copending applications, I have described my process for making intermediate or partial oxidation products from hydrocarbons, such as petroleum, petroleum distillates, shale oil and its distillates, etc. These applications mainly relate to making products, the molecules of which have, as nearly as possible, the same number of carbon atoms as the hydrocarbons used as raw material. Some of these are Serial 10 Nos. 272,567 filed January 22, 1919; 281,124 filed March 7, 1919; and 335,939 filed November 5, 1919, the latter now being Patent No. 1,759,620 of May 20, 1930.

As to certain broader claims the inventions 15 herein relate to fractionating a partial oxidation product containing oxygen derivatives of hydrocarbon, and also to the product fraction. As to other claims the present invention is designed to prepare mixtures of oxidation products and hydrocarbons, the molecules of which have 20 fewer carbon atoms than hydrocarbons of the raw material, although it is not restricted thereto. The process followed out is generally the same as in the said applications, namely, vaporizing the hydrocarbon, mixing it with air or an 25 oxygen containing gas, and in some cases, a diluent, such as steam, and passing the vapor phase mixture through a catalytic layer at a temperature between certain defined limits. As stated 30 in said applications, the temperature in the catalytic zone is below that of self-sustained combustion and preferably below a red heat.

Under one form of the present invention, I prefer to use higher temperature conditions than 35 in former types of my process, where the main products were for other than fuel uses. By using a somewhat higher temperature and a higher ratio of air, I not only effect a partial oxidation 40 of the hydrocarbons treated, but in part, decomposition of the oxidation products at the higher temperature, this giving a higher percentage of carbon monoxide and carbon dioxide in the off-take gases and producing hydrocarbons of lower carbon content than those of the mixture 45 charged. This thermal decomposition takes place to some extent in my process for making other products, but is increased by the higher temperature and higher air ratio. This thermal decomposition of the oxidation products also 50 results in the formation of oxygen derivatives of lower carbon content than the original hydrocarbons.

The temperature employed may extend from 55 230° C. up to over 400° C., and preferably is in

the upper part of this range, the air ratio being well beyond the theoretical proportions.

When the process is carried out in this manner, I find that a considerable proportion of the mixture consists of hydrocarbons of lower carbon content, a considerable amount being within the gasoline or motor spirit range, while a larger proportion is within the kerosene range. I preferably fractionally distil the product taking off, first, a lighter fraction such as the gasoline or motor spirit fraction at its usual end point, and then at a higher temperature, take a heavier fraction, such as the kerosene product up to its usual end point. The remainder of the product may then be treated for producing lubricants or other industrial products. The motor spirit range at the present time extends to about 225° C., while the kerosene range extends from this point to up to around 300° C.

The liquid fuels thus produced are of better 20 burning quality and more easily ignited than the ordinary hydrocarbon fractions within these ranges of distillation, owing to the greater content of oxygen, due to the oxidation process. The motor spirit produced may be employed in 25 all ordinary internal combustion engines and the kerosene product may be employed in many types of internal combustion engines, such as those for tractor use, etc.

The fraction within the ordinary kerosene 30 range may, if desired, be subjected to a second decomposition step of the usual "cracking" type. This cracking may be carried out in the liquid phase at temperatures giving from 100 to 300 pounds per square inch pressure, or in the pressure liquid and vapor phase or in the pressure vapor phase. Or the mixture may be cracked by high frequency, high voltage electrical oscillations in the vapor phase or liquid phase or in 35 the combined liquid and vapor phase.

As an example of one type of my process, I 40 employ a fraction of Mexican fuel oil boiling from 300° C. to 360° C. This fraction was subjected to my partial oxidation process in the three-screen apparatus of my application, Serial No. 435,355 filed January 6, 1921, now U. S. Patent 2,054,571, 45 using as a catalyst the blue oxides of molybdenum deposited on asbestos for the catalytic layer. The temperature of vaporizer being about 330° C., an amount of water equal to about ten 50 percent of the oil volume was fed with the oil to aid in vaporization. The air used was 1.5 liters per minute for every 100 cubic centimeters of oil fed per hour. The oil was fed at the rate of six liters per hour and the air was distributed to 55

the three screens, as noted in the above application. The temperature of the three catalytic screens varied from 380° C. to 400° C., during the run, which lasted for three hours.

5 The condensed, oxidized product was, in volume, equal to about 80% of the oil fed. This product contained about 30% by volume of aldehyde fatty acids and 20% by volume of aldehydes and aldehyde alcohols, the remaining 50% being made up of other oxygenated bodies, together with hydrocarbons of low molecular weight, resulting from decomposition of oxygenated bodies.

10 On distillation, the product gave 12% of a fraction boiling under 200° C. and 65% of a fraction boiling under 300° C. The oxygenated bodies are distributed through the entire range of fractions obtained by fractionally distilling the product.

15 If a heavy Mexican distillate is used or "wax" 20 distillate from the Mid-Continental oils or gas oil or other byproducts from the Pennsylvania or other oils, or "pressure tar" (a byproduct from the cracking of oils) I prefer to distil the oxidized product taking the portion about 300° C. or in 25 some cases above 300° C., as the starting point for grease manufacture or lubricating oil manufacture, as described in other co-pending applications, some of which are now patents, including Patents Nos. 1,700,055, 1,700,056, both of January 22, 1929, and 2,054,571 of September 15, 1936.

30 The fraction of the oxidized product mixture boiling below either of the above points may, in certain cases, be used as a fuel, without other 35 chemical treatment. This product, because of its oxygenated character, burns more rapidly than ordinary hydrocarbon fractions boiling between the same limits. This fraction or portions of it may be blended to make motor fuels of high 40 thermal value and ready combustibility. The entire oxidized product mixture under 300° C., may be used in kerosene tractors or all kerosene engines, where its peculiar chemical character makes it a highly efficient fuel. This total mixture fraction is also specially valuable as a fuel 45 for engines of the Diesel or semi-Diesel type, as the easy oxidizability of the fuel makes it possible to produce the development of power at lower pressures in such types of engine.

50 Or as above indicated, it may be separated by distillation into two fractions, one in the gasoline or motor spirit range and another in the kerosene range. In the latter case, on carrying out one type of cracking or further thermal decomposition of the kerosene fraction, from 55 62 to 90% of the total liquid charged was recovered, this giving from around 30 to nearly 50% of a fraction distilling below 200° C. The amount of motor spirit fuel obtained in this cracking of the 60 kerosene fraction will, of course, depend considerably upon the type of cracking process employed.

65 In all cases, that portion of the oxidation product materially distilling above the kerosene range 70 may be treated for producing industrial products, such as lubricants, greases, etc. In my claims, the words "to different degrees of oxidation" mean that chemically differing aliphatic hydrocarbon derivatives are formed in the partial oxidation step; the words "oxidized and cracked" or "cracked and oxidized" mean that the material has been oxidized and cracked, or vice versa, either as successive steps or in the same step; and the word "hydrocarbons" is used 75 in the broad sense to include hydrocarbons con-

taining hydrogen and carbon, as well as those containing hydrogen, carbon and oxygen. The fractions may be used for any desired purposes.

Changes may be made in the form of apparatus employed, the temperatures used, the methods of cracking employed, etc., without departing from my invention.

I claim:

1. The method of treating petroleum hydrocarbons, consisting in passing a mixture of finely 10 divided hydrocarbons and oxygen over a catalyst at a temperature below a red heat, thereby chemically tying oxygen into the hydrocarbons to different degrees of partial oxidation, and then separating the product into different fractions 15 of different molecular weights, the heavier fraction having a greater percentage of aldehyde fatty acids than the other fraction.

2. In the treatment of petroleum hydrocarbons which already contain artificially-introduced 20 chemically-combined oxygen to different degrees of oxidation in the range from alcohols to oxygenated organic acids some of said different bodies being within the same boiling point range, the step consisting of fractionating the same into 25 fractions of different average molecular weights each containing different bodies within the same boiling point range.

3. As a new composition of matter, a liquid 30 fractionated portion of a partial oxidation product mixture of hydrocarbons of different molecular weights and containing artificially-introduced chemically-combined oxygen to different degrees of oxidation including alcohols and aldehyde-like bodies of different molecular weights.

4. As a new composition of matter, the thermally-decomposed product of a mixture of partially-oxidized aliphatic hydrocarbons containing alcohols and aldehyde-like bodies.

5. In the treatment of liquid organic bodies of 40 the aliphatic hydrocarbon type, the steps consisting of passing a stream comprising a mixture of said bodies of different molecular weights and oxygen through a hot reaction zone at a temperature below a red heat, thereby chemically 45 tying oxygen into the bodies to different degrees of partial oxidation, and recovering and fractionating from the exit stream separate liquid fractions each containing different partially oxidized bodies, some of which different bodies are 50 within the same boiling point range, whereby liquid fractions are obtained each of different average molecular weight and each containing several different oxidized bodies within the boiling point range of said fraction and in the range 55 from alcohols to oxygenated organic acids, a lighter fraction containing a less percentage of said acids than a heavier fraction.

6. In the treatment of liquid organic bodies of 60 the aliphatic hydrocarbon type, the steps consisting of passing a stream comprising a mixture of said bodies of different molecular weights and oxygen through a hot reaction zone at a temperature below a red heat, thereby chemically tying oxygen into the bodies to different degrees of 65 partial oxidation, recovering a liquid mixture of different partially oxidized hydrocarbons from the exit stream, and fractionating the same into liquid fractions of different average molecular weights, each containing different bodies in the 70 range from alcohols to oxygenated organic acids, one of said fractions being within the motor spirit range.

7. In the treatment of a liquid mixture containing aliphatic hydrocarbons of different mo- 75

lecular weights, the steps consisting of passing a stream of the same and oxygen in contact with a catalyst at a temperature below a red heat, and recovering and fractioning from the exit stream a plurality of fractions each of different average molecular weight and each containing different oxidized bodies in the range from alcohols to oxygenated organic acids.

8. In the treatment of a liquid mixture containing aliphatic hydrocarbons of different molecular weights, the steps consisting of passing a stream of the same and oxygen in contact with a catalyst at a temperature below a red heat, and recovering and fractioning from the exit stream 5 a plurality of fractions each of different average molecular weight and each containing different oxidized bodies in the range from alcohols to oxygenated organic acids, and blending a fraction thereof with another liquid of the hydrocarbon type.

9. In the treatment of a liquid mixture containing aliphatic hydrocarbons of different molecular weights, the steps consisting of passing a stream of the same and oxygen in contact with 25 a catalyst at a temperature below a red heat, and recovering and fractioning from the exit stream a plurality of fractions each of different average molecular weight and each containing different oxidized bodies in the range from alcohols to oxygenated organic acids, and blending a fraction 30 thereof with a liquid hydrocarbon containing substantially only hydrogen and carbon.

10. In the treatment of petroleum hydrocarbons which already contain artificially-introduced 35 chemically-combined oxygen to different degrees of oxidation in the range from alcohols to oxygenated organic acids, some of said different bodies being within the same boiling point range, the steps consisting of fractionating the same into 40 fractions of different average molecular weights, each containing different bodies within the same boiling point range, and thermally decomposing a portion of a fraction thereof.

11. In the treatment of petroleum hydrocarbons which already contain artificially-introduced 45 chemically-combined oxygen to different degrees of oxidation in the range from alcohols to oxygenated organic acids, some of said different bodies being within the same boiling point range, the steps consisting of fractionating the same into 50 fractions of different average molecular weights, each containing different bodies within the same boiling point range, and thermally decomposing a portion of a fraction thereof under superatmospheric pressure.

12. In the treatment of petroleum hydrocarbons which already contain artificially-introduced 55 chemically-combined oxygen to different degrees of oxidation in the range from alcohols to oxygenated organic acids, some of said different

bodies being within the same boiling point range, the steps consisting of fractionating the same into fractions of different average molecular weights, each containing different bodies within the same boiling point range, and thermally decomposing a portion of a fraction thereof under superatmospheric pressure in the liquid and vapor phase.

13. In the treatment of petroleum hydrocarbons which already contain artificially-introduced chemically-combined oxygen to different degrees of oxidation in the range from alcohols to oxygenated organic acids, some of said different bodies being within the same boiling point range, 10 the steps consisting of fractionating the same into fractions of different average molecular weights, each containing different bodies within the same boiling point range, and subjecting a lighter fraction to thermal decomposition.

14. As a new composition of matter, a liquid mixture of aliphatic hydrocarbons of different molecular weights, a material percentage of which contains artificially-introduced chemically-combined oxygen to different degrees of oxidation in 25 the range from alcohols to oxygenated organic acids, and also containing cracked hydrocarbons.

15. As a new composition of matter, a liquid fractionated portion of a mixture of aliphatic hydrocarbons of different molecular weights, a material percentage of which contains artificially-introduced chemically-combined oxygen to different degrees of oxidation in 30 the range from alcohols to oxygenated organic acids.

16. As a new composition of matter, a liquid mixture of aliphatic hydrocarbons of different 35 molecular weights, a material percentage of which contains artificially-introduced chemically-combined oxygen to different degrees of oxidation in the range from alcohols to oxygenated organic acids, and also containing cracked hydrocarbons 40 blended with a hydrocarbon.

17. As a new composition of matter, a liquid mixture of aliphatic hydrocarbons of different molecular weights, a material percentage of which contains artificially-introduced chemically-combined oxygen to different degrees of oxidation in 45 the range from alcohols to oxygenated organic acids; and also containing cracked hydrocarbons of the character produced by thermal decomposition.

18. As a new composition of matter, a liquid lighter fractionated portion of a mixture of aliphatic hydrocarbons of different molecular weights, a material percentage of which contains artificially-introduced chemically-combined oxygen to different degrees of oxidation in 55 the range from alcohols to oxygenated organic acids, said mixture containing thermally decomposed aliphatic hydrocarbon.

JOSEPH HIDY JAMES. 60
